APPARATUS FOR INVERTING ARTICLE CONTAINERS

Emil Rothman, New York, N. Y., assignor to Edward Ermold Company, New York, N. Y., a corporation of New York

Application January 15, 1949, Serial No. 71,104

10 Claims. (Cl. 214—1.1)

1

This invention relates to apparatus for discharging materials from containers, and has particular reference to apparatus for inverting containers such as shipping cases to empty them of debris preparatory to repacking or refilling the cases with bottled goods and the like, although the invention is not limited to that use.

It is common practice to repack beer and other bottled beverage cases with refilled bottles and to that end the cases containing the empty bottles are collected and returned to the bottle shop, where the bottles are removed, cleansed, refilled and repacked into the cases. The returned cases contain debris of various kinds, usually bottle tops, broken glass, and other loose, solid pieces which can be removed simply by dumping, as by inverting the case. However, the mere inversion of the case to empty it of debris is a separate operation and where the unpacking of the bottles from the case is effected automatically, as by the machine disclosed in copending application Serial No. 785,304, filed November 12, 1947, by applicant, it is likewise desirable to effect the case cleaning operation automatically, so that the case is ready for refilling without requiring manual attention other than inspection for removing damaged cases.

In accordance with the present invention, apparatus is provided for automatically discharging debris from bottle cases as the latter leave an automatic or semi-automatic case unpacking machine, the debris discharging operation being timed with the case unpacking operation so that the two machines operate in step and the debris discharging apparatus complements the case unpacking machine.

A preferred embodiment of the invention comprises a pair of heads rotating in unison about a horizontal axis and spaced apart horizontally to receive an empty case between them. Each head carries a plurality of grippers, such as two, each gripper being positioned opposite a corresponding gripper on the other head, each gripper being actuated inwardly toward and outwardly from its opposite gripper by a stationary crown cam and each gripper being bodily rotatable simultaneously with its opposite gripper about its horizontal axis upon engagement of a pinion on each gripper with a gear segment coaxial with the axis of rotation of the corresponding head.

The gear segment and crown cam are so arranged that as an empty case is discharged by the case unpacking machine and into a position between the spaced heads of the debris discharging apparatus, the crown cams of the opposite heads advance opposite grippers toward each other so that the case is clamped securely between a pair of them and carried bodily upwardly in an arc by the grippers to the gear segment whereupon pinions on the grippers engage the gear

2

segment and rotate the case-holding grippers about their aligned horizontal axes to invert the case over a debris collecting receptacle into which the loose debris is dumped as it falls from the case. The gear segment then reverts the case to its upright position and the case is carried downwardly to a point immediately above a discharge conveyor, whereupon the crown cams release the corresponding opposite grippers for retraction by springs to deposit the cleaned case upon the discharge conveyor. A circular righting cam cooperating with a cam follower on each gripper keeps the latter from rotating until and after the gear segment performs its case inverting function.

15 It will be seen that the automatic case inverting apparatus of this invention is a simple and effective adjunct to a case unpacking machine, whereby the auxiliary function of case cleaning may be performed in synchronism with the case 20 unpacking and repacking operations without interruption for manual cleaning.

For a more complete understanding of the invention, reference may be had to the accompanying drawings, in which:

25 Fig. 1 is a side elevation, shown partly in section as seen along the line 1—1 of Fig. 2, illustrating one of the case inverting heads and a case in phantom during the successive inverting and 30 reverting steps;

30 Fig. 2 is an elevation of the case inverting apparatus as seen from the right-hand or case inlet side of Fig. 1;

35 Fig. 3 is an enlarged partial section as seen along the line 3—3 of Fig. 2, illustrating the cam for advancing the gripper to and from case gripping position, and the case inverting gear segment;

40 Fig. 4 illustrates the rollers and cam for preventing rotation of the case grippers prior and after engagement of the case-inverting pinions with the gear segment, as seen along the line 4—4 of Fig. 3, and

45 Fig. 5 is a section seen along the line 5—5 of Fig. 1 illustrating the case inverting pinion of the gripper cooperating with the gear segment.

Referring to the drawings, numeral 10 designates an infeed conveyor which may be the outfeed conveyor from a case unpacking machine M of the general nature described and whose far 50 sprocket 11 is keyed on a driven shaft 12 which operates in step with the case unpacking machine, not shown. The empty cases C are delivered by the conveyor 10 onto a horizontal platform 13, the case being deposited thereon at the 55 point indicated by C' in Fig. 1, that is, just beyond the end of the conveyor 10.

Positioned adjacent the end of conveyor 10 is the frame 14 of the apparatus for discharging the debris from case C' by inverting same

in the manner previously described. Journalled on the frame 14 and parallel to shaft 12 is a cross shaft 15 driven by a sprocket 16 connected by chain 17 to a sprocket 18 secured to shaft 12. A small pinion 19 secured on driven shaft 15 is connected by chain 20 to a large sprocket 21 keyed on a stub shaft 22 rotating in roller bearings 23 mounted in a hub 24 supported on a vertical web 25 mounted on side wall 31. A second set comprising web 25, hub 24, stub shaft 22, sprocket 21, chain 20 and pinion 19 are mounted in laterally spaced relation and parallel to the first set, so that there is one set at each side of the machine as shown particularly in Figs. 1, 2 and 3.

Keyed on each stub shaft 22 by key 26 for rotation with shaft 22 is a drum-like head as is shown particularly in Fig. 3. Each head 27 comprises a two-armed spider 28 welded to the hub 29 to which the shaft 22 is secured by key 26. The spider 28 rotates within a semicircular hood or casing 30 carried by means of bowed tubes 32 welded to horizontal plates 62 bolted to channels 63 of frame 14. The lateral wall 33 and the side wall 31 of the head 27 are welded to tubes 32. As shown particularly in Fig. 3, side wall 31 is provided with an aperture through which the shaft 22 of spider-driving sprocket 21 projects.

Journalled and also axially slidably mounted in bearings 34 secured in spaced hubs 28' welded to the ends of the two arms of spider 28 are the shafts 36 of the case grippers. As indicated in Fig. 2, two such shafts 36 are provided, although there may be more depending on requirements. Secured to the outer free end of each gripper shaft 36 is a circular plate 37 carrying a non-metallic pad or cushion 38, preferably made of rubber or other equivalent friction material for gripping the cases. It will be observed particularly in Fig. 2 that corresponding gripping pads on opposite heads 27 are axially aligned for joint case-gripping cooperation, in a manner to be described.

The opposite or inner end of each gripper shaft 36 is provided with a recess in which is rotatably inserted the pin 39 of a clevis 40, this pin having a peripheral groove 41 in which a wire keeper is positioned so that gripper shaft 36 may rotate independently of clevis 40 which carries a cam-following roller 42 engaging a stationary crown cam 43 secured by bolts 44 to the inner surface of the side wall 31 of each head 27. The cam 43 is provided with side flanges 45 for guiding the roller 42 and for preventing it from rotating with the corresponding gripper shaft 36. It will be observed that in following the cam 43 the cam roller 42 causes the shaft 36 and pad 38 of the corresponding gripper 35 to move axially inwardly and outwardly in accordance with the contour of the cam 43, which will be described in greater detail.

Secured by bolts 46 to the edge of each stationary web 25 and concentrically with the axis of rotation of gripper spider 28 is an interrupted horseshoe-shaped circular cam 47 shown especially in Figs. 1, 3 and 4. Engaging the edge of the interrupted cam 47 are two of the four cam-following rollers 48 journalled on a rectangular plate 49 secured on the inner end of each gripper shaft 36 as shown in Figs. 3 and 4. It will be observed that when two of the four rollers 48 are in engagement with cam 47 the corresponding gripper shaft 36 and its gripper pad 38 are prevented from rotating, and may rotate only when rollers 48 are disengaged from cam 47, i. e., when

they have passed off of the end of the cam 47 into the interrupted space 47', shown in Fig. 1, and before two of the four rollers 48 reengage the cam 47 at the other side of the space 47'.

Splined by means of key 50 on each gripper shaft 36 is a pinion 51 which is continuously urged into engagement with flange 34' on bearing 34 by coil spring 52 encircling shaft 36 and engaging plate 49 at its other end, as is best shown in Figs. 3 and 5. Because plate 49 is secured to shaft 46, the pressure of spring 52 against plate 49 also serves to urge cam-following roller 42 against the track of crown cam 43 so that roller 42 follows the cam 43 without vibration during operation. Each pinion 51 lies in the vertical plane of gear segment 53 which is mounted by tap bolts 54 to bosses 55 on stationary center web 25 and concentrically with the axis of rotation of gripper spider 28, as shown particularly in Fig. 5. It will be observed from Fig. 1 that gear segment 53 has the same angular position as the gap 47' in horseshoe-shaped cam 47, and extends slightly beyond the same at each side. In effect, gear segment 53 cooperating with cam 47 jointly constitute an interrupted circular gear, whereby when cam 47 frees gripper shaft 36 for rotation of a gripper 35 about its axis, the corresponding pinion 51 engages gear segment 53 and causes gripper 35 to rotate for a purpose to be described.

Located opposite the incoming conveyor 10 is a discharge conveyor 56, which may be the inclined gravity conveyor shown, for receiving discharged cases in the manner to be described.

Located below and between the two heads 27 is an open-top debris box 57 which may be removed for emptying and replaced on the center vertical line of the machine; as indicated in Figs. 1 and 2.

Adjustments are provided for laterally locating the machine relatively to the frame of the case unpacking machine M, this adjustment being afforded by bolts 58 passing through vertical slots 59 in plates 60 secured to frame 14, as shown in Figs. 1 and 2. By means of these bolts 58, the cases C discharging to position C' may be accurately centered horizontally with respect to the circular path of the grippers 35, as indicated in Fig. 1. Similarly, by means of vertical adjusting bolts 61 the elevation of the frame 14 may be adjusted so that the grippers 35 when aligned horizontally, as shown in Fig. 1, lie opposite the horizontal center line of the case C' when actuated by cam 43 to grip the case C'. Also, bolts 64 securing the plates 62 of head 27 to frame 14 pass through slots 65 in channels 63 permitting lateral adjustment of the head 27. Other adjustments suited to requirements may be made.

In operation of the case inverting and cleaning apparatus of this invention, the infeed conveyor 10 deposits cases C on platform 13 in position C' after the cases have been emptied of their contents such as bottles, but while the cases still contain debris such as bottle caps, broken glass, and the like. The timing of cam 43 is so arranged that as a case C is deposited on platform 13 in the position indicated by C', cam 43 urges opposite grippers 35 inwardly to engage the opposite ends of the case C' and grip the latter securely between them at the approximate intersection of the vertical and horizontal center planes of the case C'.

Spiders 28 of the opposite heads 27 are being rotated continuously in a counter-clockwise di-

rection as seen in Fig. 1 by the sprocket and chain combination 19, 20, 21, so that a case in position C', after engagement by the grippers 35 in the manner described, is lifted from platform 13 and carried bodily upwardly by spider 28 and grippers 35 through the corresponding arc toward the top of the machine, meanwhile being kept in an approximate upright position by the cam-following rollers 48 engaging horseshoe cam 47. Toward the top of the machine, cam-following rollers 48 run off the end of cam 47 into space 47' while pinions 51 of the opposite functioning grippers 35 engage gear segment 53 to rotate the corresponding grippers 35 so as to rotate the case from the upright to the inverted position C'' at the top of the machine, as is shown in phantom in Fig. 1. In the inverted position C'' in Fig. 1, any debris in the case falls by gravity into the receptacle 57, the free fall of the debris being uninterrupted by reason of the open space between the heads 27 as is best shown in Fig. 2.

The rotation of the case from the upright position C' to the fully inverted position C'' at the top of the machine is such as to effect about 180° of rotation and from the inverted position at C'' to the position C''', the case is again rotated through about 180° to restore it to its substantially upright position at C'''. This rotation is effected jointly by the tilt of the case in its upward course through the arc of cam 47 to its end at gap 47', which is preferably about 54°, and then by segment 53, which preferably imparts a rotation of about 252° to the case, which takes it beyond the fully inverted position C''. Consequently, when pinions 51 run off the ends of the gripper gear segments 53 and the cam followers 48 reengage cam 47, the case has been emptied of its debris. During its course down cam 47 to lowered position C''' the case moves through about 54°, having made a 360° revolution, and is ready for release from the machine at position C''', shown in Fig. 1. At this point, cam 43 releases cam-follower 42 and the corresponding spring 52 retracts the gripper 35 from the case at opposite sides of the machine, so that the case is dropped onto the outfeed conveyor 56 for discharge, as indicated in Fig. 1.

It will be observed that during rotation of the grippers 35 with the case by gear segments 53, plates 49 and rollers 48 also are bodily rotated, so that the two rollers 48 which reengage cam 47 are not the same rollers 48 that left the cam 47 at gap 47' but the opposite pair of rollers 48.

Case infeed timing is preferably such that one of the two sets of opposite grippers 35 engages an incoming case when the other set discharges a cleaned case. The machine is adjustable for different size cases by spacing the heads 27 apart on frame 14 by means of bolts 64 cooperating with the horizontal slots 65 in frame channels 63 shown in Fig. 2, and as previously indicated, the positioning of the case with respect to the center line of the inverting machine is adjusted by bolts 58 for horizontal adjustment, and by bolt 61 for vertical adjustment.

Although a preferred embodiment of the invention has been illustrated and described herein, it is to be understood that the invention is not limited thereby, but is susceptible to changes within the scope of the appended claims.

I claim:

1. In a container inverting apparatus, the combination of a pair of spaced opposite gripping

members adapted to receive a container between them, feed mechanism for positioning a container between said members, means advancing at least one of said members along a common axis toward the other member to grip the container between them, a mounting for said members for simultaneous movement about an axis parallel to said axis, means driving said members about said parallel axis to bodily move said container, a segment concentric with said parallel axis, a wheel on said gripping members and tangent to said segment for rotation thereby to invert the container, and means for disengaging said grippers from said container after said inversion.

2. In a container inverting apparatus, the combination of a pair of spaced opposite gripping members adapted to receive a container between them, feed mechanism for positioning a container between said members, means advancing at least one of said members along a common axis toward the other member to grip the container between them, a mounting for said members for simultaneous movement about an axis parallel to said axis, means driving said members about said parallel axis to bodily move said container, a gear segment concentric with said parallel axis, a gear wheel on said gripping members and tangent to said segment for rotation thereby to invert the container, and means for disengaging said grippers from said container after said inversion.

3. In a container inverting apparatus, the combination of a pair of spaced opposite gripping members adapted to receive a container between them, feed mechanism for positioning a container between said members, means advancing at least one of said members along a common axis toward the other member to grip the container between them, a mounting for said members for simultaneous movement about an axis parallel to said axis, means driving said members about said parallel axis to bodily move said container, a segment concentric with said parallel axis, a wheel on said gripping members and tangent to said segment for rotation thereby to invert the container, holding means concentric with said segment for preventing rotation of said gripper members prior to engagement of said wheel with said segment, and means for disengaging said grippers from said container after said inversion.

4. In a container inverting apparatus, the combination of a pair of spaced opposite gripping members adapted to receive a container between them, feed mechanism for positioning a container between said members, means advancing at least one of said members along a common axis toward the other member to grip the container between them, a mounting for said members for simultaneous movement about an axis parallel to said axis, means driving said members about said parallel axis to bodily move said container, a segment concentric with said parallel axis, a wheel on said gripping members and tangent to said segment for rotation thereby to invert the container, holding means on said gripper members engaging said track for preventing rotation of said gripper members prior to engagement of said wheel with said segment, and means for disengaging said grippers from said container after said inversion.

5. In container inverting apparatus, the combination of a pair of spaced opposite gripping

members adapted to receive a container between them, feed mechanism for positioning a container between said members, means advancing at least one of said members along a common axis toward the other member to grip the container between them, a mounting for said members for simultaneous movement about an axis parallel to said axis, means driving said members about said parallel axis to bodily move said container, a circular track concentric with said segment, holding means on said gripper members engaging said track for preventing

members adapted to receive a container between them, feed mechanism for positioning a container between said members, a support mounting said members for rotation about their common axis, means mounting said support about an axis parallel to said common axis, a stationary cam for first advancing and then retracting at least one of said members along said common axis, whereby said container is first gripped between said opposite members and then released, a segment concentric with said parallel axis, a wheel on said gripper members and tangent to said segment for rotating said members about said common axis after said container is gripped thereby to rotate said container through an inverted position, and receiving means for said container after release by said cam.

6. In container inverting apparatus, the combination of a pair of spaced opposite gripping members adapted to receive a container between them, feed mechanism for positioning a container between said members, a support mounting said members for rotation about their common axis, means mounting said support about an axis parallel to said common axis, a stationary cam for first advancing and then retracting at least one of said members along said common axis, whereby said container is first gripped between said opposite members and then released, a gear segment concentric with said parallel axis, a gear wheel on said gripper members and tangent to said segment for rotating said members about said common axis after said container is gripped thereby to rotate said container through an inverted position, and receiving means for said container after release by said cam.

7. In container inverting apparatus, the combination of a pair of spaced opposite gripping members adapted to receive a container between them, feed mechanism for positioning a container between said members, a support mounting said members for rotation about their common axis, means mounting said support about an axis parallel to said common axis, a stationary cam for first advancing and then retracting at least one of said members along said common axis, whereby said container is first gripped between said opposite members and then released, means including an interrupted gear concentric with said parallel axis and a corresponding pinion on each of said members for rotating said members about said common axis after said container is gripped thereby to rotate said container through an inverted position, and receiving means for said container after release by said cam.

8. In container inverting apparatus, the combination of a pair of spaced opposite gripping members adapted to receive a container between them, feed mechanism for positioning a container between said members, a support mounting said members for rotation about their common axis, means mounting said support about an axis parallel to said common axis, a stationary cam for first advancing and then retracting at least one of said members along said common axis, whereby said container is first gripped between said opposite members and then released, a segment concentric with said parallel axis, a wheel on said gripper members and tangent to

said segment for rotating said members about said common axis after said container is gripped thereby to rotate said container through an inverted position, holding means concentric with 5 said segment for preventing rotation of said members prior to engagement of said wheel with said segment, and receiving means for said container after release by said cam.

9. In container inverting apparatus, the combination of a pair of spaced opposite gripping members adapted to receive a container between them, feed mechanism for positioning a container between said members, a support mounting said members for rotation about their common axis, means mounting said support about an axis parallel to said common axis, a stationary cam for first advancing and then retracting at least one of said members along said common axis, whereby said container is first gripped between 10 said opposite members and then released, means including an interrupted gear concentric with said parallel axis and a corresponding pinion on each of said members for rotating said members about said common axis after said container is gripped thereby to rotate said container through an inverted position, a track concentric with said gear, a pair of spaced rollers on each gripper member engaging said track for preventing rotation of said members prior to engagement of 15 said pinions with said gear, and receiving means for said container after release by said cam.

10. In container inverting apparatus, the combination of a pair of spaced opposite gripping members adapted to receive a container between them, feed mechanism for positioning a container between said members, a support mounting said members for rotation about their common axis, means mounting said support about an axis parallel to said common axis, a stationary cam for 20 first advancing and then retracting at least one of said members along said common axis, whereby said container is first gripped between said opposite members and then released, means including an interrupted gear concentric with said parallel axis and a corresponding pinion on each of said members for rotating said members about said common axis after said container is gripped thereby to rotate said container through an inverted position, a track concentric with said gear 25 and having an interrupted segment having substantially the same radial angle length and position as the toothed segment of said interrupted gear, followers on each gripper member tangent to said track for preventing rotation of said members prior to engagement of said pinions with said gear, and receiving means for said container after release by said cam.
